FEED APPARATUS WITH LOCK CHAMBERS FOR HYDRAULIC CONVEYING

Oszkár Hrabovszky and Levente Pányi, Budapest, Hungary, assignors to Licencia Találmányokat Értékesítő Vállalat, Budapest, Hungary

Filed Nov. 25, 1957, Ser. No. 698,509

Claims priority, application Hungary Dec. 1, 1956

3 Claims. (Cl. 302—14)

The invention is primarily intended for use in mining, where the mined raw material is mainly conveyed up through vertical shafts by means of shaft winding engines. The disadvantage of this method consists in that a good deal of dead weight in the form of cages, tubs etc. has to be moved together with the conveyed useful weight, thus requiring large shaft cross-sections, and requiring the services of a considerable amount of personnel.

According to an earlier patent, it was proposed, for the shaft haulage of mined material, to use principally the water which wells up in the pits and is available in any case and has in fact to be conveyed out of the pit, or else to use water specially introduced for this purpose. The installation must be so arranged that the water is introduced into the conveying pipe in as pure a condition as possible by means of a high-pressure pump, expediently a centrifugal pump, and the material (coal ore) is introduced into this stream of water by means of a feed apparatus. The mixture when brought to the surface is freed of water through screens, and the small grains, e.g. the fine coal, is separated from the water by clarification. Alternatively, the mixture can be conveyed directly into the washing plant.

This development permits uniform vertical shaft haulage in the stationary installation, i.e. the haulage of the material from the pit to the surface can be carried out continuously and without any interruptions.

The invention relates to a feed apparatus with lock chambers wherein the mixture is drawn by suction from the quantity regulating hopper into the pressure chamber by means of a piston cylinder during the period of charging the ore, coal or other materials. In this way the quantity regulation of the solid material is accelerated.

According to a further feature of the invention, the upper cylinder is also used for accelerating the solid material into the high-pressure stream of water which forces the mixture out of the pressure chamber into the mixing chamber.

The invention also proposes using such connecting means as to connect on the one hand the lower end of the cylinder to the pressure chamber and on the other hand the upper end by means of a change-over valve, either to the part of the conveying pipe in which only pure water flows, or to the feed chamber, for the purpose of providing the same pressure simultaneously at both sides of the piston whilst the cylinder is in operation.

According to a further feature of the invention, the aforesaid piston cylinder takes from the pure-water conveying pipe a quantity of water equal to the volume of solid material introduced into the conveying pipe, in order that the introduction of material into the conveying pipe does not produce any pressure difference.

The invention is also characterised in that the feed apparatus has a feed hopper with double walls which is equipped with means for producing an overflow of pure water equal to the measured volume of coal, ore or like material.

The invention, i.e. the feed apparatus can also be

2

so constructed that the accelerating piston cylinder feeds to the outer chamber of the feed hopper during the suction period the same quantity of water as is taken, i.e. taken by suction, from the inner chamber of the hopper during the feed period, whereby the overflow of water at the overflow pipe will always be equal to the measured-off volume of solid material.

According to a further development of the invention, the feed installation can be provided with hydraulically operated valves for shutting off the lock chambers.

A further development of the invention provides between the lock chambers, valves for pressure equalisation and air evacuation, and which are also used for the flow of water for closing or opening the aforesaid valves hydraulically.

Finally, the invention is characterised further in that, for the purpose of isolating the lock chambers, it is provided with valves which are movable hydraulically or mechanically on tracks. One form of embodiment of the apparatus developed according to the invention is illustrated in the accompanying drawings.

In the drawings, Figure 1 is a longitudinal sectional view of the apparatus, and Figure 2 is a cross-sectional view on A—A of Figure 1.

With the apparatus according to the invention feed is periodic, and the method of operation of the apparatus will be described by describing the events of one working period.

Material is fed into the upper hopper 1 of the chamber A through the tubular aperture 2 at the top of the said chamber. Before quantity regulation, the water in the chamber A is at the level X; at the same time, the valve 3 in its lower position illustrated in the drawings cannot block the aperture between the chambers A and B, i.e. cannot separate the chambers from one another.

When material is fed into the said hopper, the water level in the chamber A rises by an amount corresponding to the fed-in volume of solid material to the height y, and in the outer chamber to the height z. Then the piston 4a begins to move in the cylinder 4, being moved upwards out of its lower position illustrated in the drawings as a result of mechanical or hydraulic action in the cylinder, and in so doing subjects the chamber A to a suction effect through the conduit 5 which connects with the chamber B.

As a result of this action, the downward flow of the solid constituents descending in the water in the chamber A is accelerated, i.e. their passage into the chamber B is promoted. At this time, the upper aperture of the cylinder chamber 4 is made to communicate with the outer hopper space 7 of the chamber A by the appropriate adjustment of the change-over valve 6 and through the conduit 20, the piston 4a conveying to the said space 7 the quantity of pure water situated above the said piston. This inflow of pure water reaches a temporary maximum level u when the piston is in its uppermost position, and the water level in the inner hopper chamber A drops at the same time to s. Owing to the difference between the levels u and s between the outer and inner chambers, pure water flows from the outer chamber through the aperture 10 into the inner chamber.

The overflow valve 8 and the aperture 10, whose dimensions are adjustable, must be so regulated that at the end of the period the average level x should be reached both in the inner chamber and in the outer chamber. Thus through the aperture 10 a flow will always be produced in the direction from the chamber 7 into the chamber A, i.e. there is always pure water in the chamber 7 and pure water also flows out through the valve 8 and overflow pipe 9. In this way it is ensured that no coal can get into the pipe, and even the suspended grains are conveyed immediately out of the chamber A towards the conveying pipe.

70

3

During the suction period a similar atmospheric pressure prevails in the chambers A and B. At the end of the feed period the aerodynamically shaped shutoff valve 3, which is arranged on the three-armed valve carrier 11 (shown in detail in Figure 2) and on the valve support 12, begins to ascend owing to the hydraulic piston-cylinder arrangement with which it is provided internally, completely shutting off the aperture between the chambers A and B.

One of the three arms illustrated in Figure 2, the arm designated with the reference numeral 14, is perforated with a through bore. This bore is in communication with the lower half of the likewise internally cylinder-shaped valve support 12, and the piston (not shown) formed by the lower end of the valve stem 3, moved upwards and downwards under the effect of the hydraulic pressure or suction.

After the valve 3 is closed, the change-over valve 13 changes to a position (not shown in the drawings) such that it allows the chamber B preferably to communicate with the chamber C and shuts off the chamber A from the two aforesaid chambers. The high working pressure always prevails in the chamber C. The said actuation of the change-over valve 13 now causes the high working pressure to prevail in the chamber B also. After pressure equilibrium effected by valves 13 and 6 between the chambers B and C has been achieved, the valve 15 which hitherto separated the chamber B from the chamber C and is identical in construction to the valve 3 and is similarly operated, begins to open.

Simultaneously with the actuation of the valve 13, the change-over valve 6 causes the cylinder chamber 4 above the piston 4a to communicate with the zone 16 of the conveying pipe in which still only pure water is conveyed under the high working pressure. Thus at both sides of the piston in the cylinder, high working pressure prevails. Then the compression period of the piston cylinder commences, i.e. the piston begins to move downwardly. For the further operation of the piston, it is only necessary to supply a small amount of energy to the piston rod in order to overcome frictional loss. Under the action of the pressure period the solid material fed to the chamber C is conveyed partly as a result of its own weight and partly owing to the acceleration caused by the piston pressure, into the stream of water in the conveying pipe 16, and the mixture thus produced is conveyed to the surface in the conveying pipe. At the end of the compression period the chamber B is completely free and the chamber C free for the most part of the grains of solid material, and therefore the valve 15 can now be closed, said valve closing the aperture between the chambers B and C through the agency of the three-armed valve carrier 17 and the vertical valve support 18 (by a method of operation in every way similar to that described with reference to the parts 11 and 12). After the change-over valve 13 has been adjusted, the chambers A and B are again put in communication with one another and in the chamber B the pressure suddenly falls to atmospheric pressure. At the same time the change-over valve 6 connects the cylinder chamber 4 above the piston 4a with the outer chamber 7 of the feed chamber. The sudden pressure equilibrium produced between the chambers A and B

4

owing to the change-over then allows the valve 3 to open and ensures that the valve 15 blocks its associated aperture completely. With the opening of the valve 3 one entire feed cycle is completed and the whole process can be repeated again from the beginning.

For the hydraulic movement of the valve 3, a flow of pure water can be used for closing purposes, said flow being under approximately atmospheric pressure, and a branched-off stream from the pure water flowing under high working pressure in the pipe 16 can be used for operating the hydraulic piston cylinder which is adapted to move the valve 15.

It should be mentioned that the aforesaid form of embodiment of the apparatus is only intended as an example. The invention also covers various other solutions, e.g. it is possible within the scope of the invention to combine two feed apparatuses for working together, whereby the quantity of solid materials fed to the conveying pipe is doubled and the mixture is conveyed more uniformly through the conveying pipe.

Having now particularly described and ascertained the nature of our invention and in what manner the same is to be performed, we declare that what we claim is:

1. An apparatus for feeding solid substances into a stream of liquid flowing through a conduit, comprising an upper feeding chamber, a jacket surrounding the feeding chamber and provided with an orifice of adjustable size affording communication between the feeding chamber and surrounding jacket, an intermediate pressure chamber communicating at its upper end with the lower portion of the feeding chamber, a lower mixing chamber communicating at its upper end with the intermediate pressure chamber, means connecting the lower end of the mixing chamber to the liquid conduit, valve means operable to close and open communication between the feeding chamber and intermediate pressure chamber and to close and open communication between the intermediate pressure chamber and the mixing chamber, a double-acting reciprocating accelerating pump having a cylinder and a piston, means connecting one end of the cylinder to the intermediate pressure chamber, means connecting the other end of the cylinder to said jacket and to the liquid conduit, and a change-over valve for alternately placing said other end of the pump cylinder in communication with the jacket and liquid conduit.

2. A feeding apparatus according to claim 1 in which said jacket includes a drain pipe with a throttle valve, and means regulating the amount of liquid in the space between the surrounding jacket and the feeding chamber, in consequence of which liquid will discharge through the drain pipe equal to the volume of the fed solid substances.

3. A feeding apparatus according to claim 1 including valve means connecting the intermediate pressure chamber alternately to the feeding and mixing chambers to equalize the pressure therebetween during reciprocating movement of the piston.
